UNITED STATES PATENT OFFICE.

JOHN N. JOHNSON, OF ALBUQUERQUE, NEW MEXICO.

CONVERTIBLE HAIR-CLIPPER.

1,351,041.

Specification of Letters Patent. Patented Aug. 31, 1920.

Application filed December 16, 1919. Serial No. 345,199.

To all whom it may concern:

Be it known that I, JOHN N. JOHNSON, a citizen of the United States, residing at Albuquerque, in the county of Bernalillo 5 and State of New Mexico, have invented certain new and useful Improvements in Convertible Hair-Clippers, of which the following is a full, clear, and exact description.

The object of this invention is to provide 10 clippers which are susceptible of either power or manual operation as desired and particularly those in which the conversion from one form of operation to the other can be quickly and easily accomplished and 15 which are simple in construction, reliable and efficient in operation and inexpensive to manufacture.

A further object is to provide power operating clippers in which the rate of operation 20 can be mechanically varied within certain limits, and to provide improved power operating means.

In carrying out my invention I provide a 25 reciprocating cutter operated by an oscillating armature which has a string arm extension and an adjustable ball or weight on the free-end of the extension. Magnets are disposed on opposite sides of the armature and their activity is controlled by a forked 30 contact arm which is oscillated by the armature or its extension. The forked arm carries adjustable contacts leading to the opposed magnets. The main circuit is controlled by a switch, one part of which is operated by the pivoted handle of the clipper. 35 To enable conversion of the clippers from power to manual operation, a manually operated member is provided which, when shifted, forces the spring extension to one extreme position and yieldingly holds the armature in a corresponding position, while intermediate linkage operated by the manually operated member interposes a slidable member between the pivoted clipper handle 40 and the flat spring at a point adjacent the armature. With this setting of the various parts, an operation of the pivoted clipper handle will, through the interposed slidable member, transmit movement to the armature 45 and thus to the cutter and at the same time flex the spring extension of the armature. When the pivoted clipper handle is released the spring extension of the armature will cause the cutter and armature to return to 50 their former positions and through the interposed slidable member will restore the

clipper handle to normal position. A return movement of the manually operated member resets the clipper for power operation.

In the accompanying drawings:

Figure 1 is a plan of clippers constructed in accordance with my invention, and with the covers removed to show the interior mechanism, the clippers being set for electrical operation.

Fig. 2 is a similar view, but with the clippers set for manual operation.

Fig. 3 is a vertical section of the clippers, but with the covers in place, and

Fig. 4 is a diagram illustrating the circuit connections.

I provide a relatively stationary cutter plate 1 having cutter teeth 2, and a fixed handle 3. A handle 4 is pivoted to the plate 1 at 5 and is limited in its outer movement by the lug 6 on the plate 1. A movable cutter plate 7 is arranged to slide upon the plate 1 and carries cutting teeth at its forward edge to coöperate with those of the stationary cutter plate 1. The plates 1 and 7 may be recessed as at 8 and 9 respectively, so as to provide for a better bearing contact between them and thus avoid any rocking of the plate 7 on the plate 1. A cover 10 has a rib 11 fitting into a longitudinal groove 12 of the plate 7 to guide it in its reciprocatory movement. The cover is held against displacement by means of lugs 13 thereon which project into recesses 14 in the fixed plate, and against removal by a screw 15. The square head 16 of the screw is received within a square hole 17 in the fixed plate 1 so as to be flush therewith and be held against rotation, and a nut 18 and spring washer 19 on the screw bear against the cover to hold its against removal and to exert an adjustable pressure upon the movable cutter plate 7.

The fixed handle 3 carries a supporting 100 plate or casing 20 of suitable non-magnetic material upon which is pivoted as by screw 21, the operating lever 22, one arm 23 of which extends within the cover 10 and into a slot 24 in the cutter plate 7 whereby oscillation of the lever will reciprocate the cutter plate 7. The screw 15 passes through an aperture 25 in the lever, and the engagement of the end walls of the aperture with the screw limits the movement of the lever 105 and thus of the cutter plate. Disposed on opposite sides of the arm 26 of the lever are

electromagnets 27 and 28 for producing oscillations of the lever. The arm 26 may be of suitable material so as to itself constitute an armature, or it may have an armature attached thereto. Carried by the plate or casing 20 and insulated therefrom are contact posts 29 and 30 having adjustable contacts 31 and 32 thereon. The contact post 29 is connected to the electromagnets 5 27 which are disposed on the opposite side of the lever therefrom, and the contact post 30 is connected to the electromagnets 28 disposed on the opposite side of the lever therefrom. The plate or casing 20 carries a U-shaped contact lever 33 pivoted at 34, and the arms of which have ends upturned on opposite sides of the lever arm 26. The upturned arms carry adjustable contacts 35 and 36 for coöperation with contacts 31 and 32 10 to control the activity of the electromagnets, dependent upon the position of the lever 33. The lever 33 has a projection 37 thereon which coöperates with a V-shaped portion 15 of a spring arm 38 to hold it at one side or the other of a central position. When the lever 33 is moved through its central position in either direction, the co-action between the V-shaped portion of the spring arm 38 and one side or the other of the projection 37 will exert a force tending to continue the movement in that direction. A flat spring extension 39 of the lever arm 26 passes between the upturned ends of the arm 33 and since it oscillates with the lever 20 it shifts the lever 33 through its central position to cause engagement of contacts 35 and 36 with contacts 31 or 32. A post 40 is carried by and insulated from the plate or casing 20, and in turn carries a spring 25 contact arm 41 adapted to be depressed into engagement with fixed contact post 42 by an insulated lug 43 on the pivoted handle 4, projecting through the casing 20 for this purpose. The contact post 42 is electrically 30 connected to the lever 33, and contact post 40 is connected to one of the main circuit wires 44, the other main circuit wire 45 being connected as a common return to the electromagnets 27 and 28. A weight 46 is shift- 35 ably mounted on the spring extension 39 of the operating lever and in accordance with its distance from the pivot of the lever it will vary the period of oscillation within certain limits. The electromagnets are 40 preferably elliptical in cross section in order to keep their thickness as small as possible. In operation, when the pivoted handle is moved inwardly toward the fixed handle, the contact 41 will be carried to engage 42 45 and close the operating circuit. Current will pass from contact 42 to lever 33 and when the lever 26 is in the position illustrated in Fig. 1, the current will pass through contact 36 of the lever to the adjustable contact 32 on contact post 30 thence

to the electromagnets 28 and through the common return wire 45 back to the main circuit. This will energize electromagnets 28 and the lever 26 will be attracted and moved toward them, and in doing so will 70 produce a movement of the cutter plate 7. During this movement of lever 26, the extension 39 will engage contact 35 and shift the lever 33 past its central position. As soon as lever 33 passes the central position 75 the spring member 38 will, through projection 37, assist in completing the movement of this lever, and bring contact 35 into engagement with contact 31 to close the circuit through the electromagnets 27. Early in 80 the movement of lever 33, however, the circuit through electromagnets 28 is broken by the separation of contacts 36 and 32. Energization of electromagnets 27 will cause attraction and movement of lever arm 26 toward them with a resultant reverse movement of the cutter plate 7, and a reverse movement of lever 33 will be produced. Thus during the engagements of the contacts 41 and 42 the oscillatory movement of 85 the lever 22 and of the cutter plate 7 will continue. By adjustment of the contacts 31, 32, 35 and 36 the magnets can be kept closed for a longer or shorter portion of the stroke of the armature lever, and the 90 throw of the armature may also be varied to some extent.

The mechanism by which I convert the clipper to enable manual operation will now be described. A link 47 is slidably and pivotally mounted on a pin 48 of the base or casing 20, by means of a slot 49 therein. A bell crank 50 is pivoted on the base and one arm 51 thereof is pivotally connected to one end of a link 52, the other end of this link 105 being pivotally connected at 53 to the link 47. The end of the casing 20 has a slot 54 in which the shank of a screw 55 carried by a block 56 arranged on the interior of the casing is adapted to slide. Tightening of the screw 55 will clamp the block 56 at any position along the slot 54. When the block is shifted from the Fig. 1 to the Fig. 2 position, the advance end of the block engages and turns arm 50^a of the bell 110 crank 50 to shift the link 47, by means of link 52, along and about pin 48 from the Fig. 1 to the Fig. 2 position. After the required movement of the bell crank, the arm 50^a thereof will ride along the side of the 115 block and permit of further movement of the block to bring an upwardly extending portion 57 thereof against the spring extension 39 of the lever 22, and move the spring and lever to the Fig. 1 position, and with the 120 spring 39 abutting against a pin 58 carried by link 47 to hold the latter upwardly, as far as possible, on the pin 48 against the lug 59 of the pivoted handle 4, as shown in Fig. 2. The screw 55 is tightened to secure the 125 130

block 56 in this position. Any movement now of pivoted handle 4 will cause lug 59 thereof to engage an offset end 47^a on the link 47 and slide the link on pin 48, which movement is permitted by the slot 49, and this will cause pin 58 of the link to move lever arm 26 about its axis with a corresponding movement of the cutter plate 7. At the same time the spring extension 39 will be flexed upon the block extension 57 so that when the pivoted handle 4 is released, the flexed spring will restore the lever 22 to the Fig. 1 or 2 position and provide a return movement of the cutter plate 7. The clipper can thus be operated manually as long as desired, but during this operation the main circuit is of course disconnected. By sliding the block 56 back to the Fig. 1 position the bell crank will be restored to Fig. 1 position by means of a spring 60 secured thereto and having its other end anchored to the casing 20. The restoring of the bell crank will restore link 47 to the Fig. 1 position by means of the connecting link 52. This leaves the clipper in condition to be electrically operated.

I claim:

1. A clipper comprising relatively movable cutter plates, power operated means for producing relative movement of the plates, manually operated means for also producing relative movement of the plates, and means for selectively rendering the manually operated means, effective or ineffective in producing relative movement of the plates.

2. A clipper comprising a fixed cutter plate and a movable cutter plate, a lever for operating said movable cutter plate, power operated means for operating said lever, manually operated means for also operating said lever, and means for selectively rendering said manually operated means effective or ineffective upon said lever.

3. A clipper comprising a fixed cutter plate and a movable cutter plate, a lever for operating said movable cutter plate electromagnets acting on said lever to operate it, controlling means for said electromagnets operated by the lever, manually operated means for operating the lever, and means for selectively rendering said manually operated means effective or ineffective upon said lever.

4. A clipper comprising a fixed cutter plate and a movable cutter plate, a lever for operating said movable cutter plate, electrical means for causing oscillations of said lever and means carried by said lever for controlling its rate of oscillation by the said electrical means.

5. A clipper comprising a fixed cutter plate and a movable cutter plate, a lever for operating said movable cutter plate, electrical means for causing oscillations of said

lever, and means adjustably carried by said lever for variably controlling its rate of oscillation caused by the electrical means.

6. A clipper comprising a fixed cutter plate and a movable cutter plate, a lever for operating said movable cutter plate, electrical means for causing oscillations of said lever, a shiftable weight on said extension for variably controlling the rate of oscillation caused by the electrical means.

7. A clipper comprising a fixed cutter plate, a movable cutter plate, a stationary handle, a pivoted handle, a lever for operating said movable cutter plate, power operated means carried by the stationary handle for causing oscillations of said lever, and shiftable means for operatively connecting and disconnecting the pivoted handle and lever to enable operation of said lever by said pivoted handle.

8. A clipper comprising a fixed cutter plate, a movable cutter plate, a stationary handle a pivoted handle a lever for operating said movable cutter plate, power operated means carried by the stationary handle for causing oscillations of said lever, a slideable member and manually operated means for interposing the slideable member between the pivoted handle and said lever to enable operation of the lever from the pivoted handle.

9. A clipper comprising a fixed cutter plate, a movable cutter plate, a stationary handle, a pivoted handle, a lever for operating said movable cutter plate, power operated means carried by the stationary handle for causing oscillations of said lever, a slideable member, a manually operated member intermediate mechanism, operated by said manually operated member for interposing said slideable member between the pivoted handle and the pivoted lever to enable operation of the lever by the handle.

10. A clipper comprising a fixed cutter plate, a movable cutter plate, a stationary handle, a pivoted handle, a lever for operating the movable cutter plate, a spring extension of said lever, a support carried by the stationary handle, power operated means on said support for operating said lever, a pin carried by said support, a link mounted for pivotal and sliding movement on said pin, and manually operated means carried by said support for shifting said link about said pin to interpose it between the pivoted handle and the spring extension and enable operation of the lever from the pivoted handle.

11. A clipper comprising a fixed cutter plate, a movable cutter plate, a stationary handle, a pivoted handle, a lever for operating the movable cutter plate, a spring extension of said lever, a support carried by the stationary handle, power operated means on said support for operating said

- lever, a pin carried by said support, a link mounted for pivotal and sliding movement on said pin, and manually operated means carried by said support for shifting said 5 link about said pin to interpose it between the pivoted handle and the spring-extension and enable operation of the lever from the pivoted handle, said manually operated means being also engageable with the spring 10 extension of the lever to hold the pivoted lever, and through it the link and pivoted handle, yieldingly one extreme position and to return them to this position after each manual operation of the pivoted handle.
- 15 12. A clipper comprising a fixed cutter plate, a movable cutter plate, a lever for operating said movable cutter plate, electromagnets placed on opposite sides of said lever to oscillate it and thereby the movable 20 cutter plate, a pivoted contact member operated from one position to the other by said lever, a spring member coöperating with said pivoted contact member to yieldingly hold the contact member to either side of a 25 central position whereby when the contact member is moved through the central position, the spring member will exert a force to complete the movement in the same direction, and stationary contacts coöperating 30 with said pivoted contact member to control the activity of said electromagnets, dependent upon the position of the lever.
13. A clipper comprising a fixed cutter plate, a movable cutter plate, a lever for operating said movable cutter plate, electromagnets placed on opposite sides of said lever to oscillate it and thereby the movable cutter plate, a pivoted contact member operated from one position to the other by 35 said lever, a spring member coöperating with said pivoted contact member to yieldingly hold the contact member to either side of a central position whereby when the contact member is moved through the central position, the spring member will exert a force to complete the movement in the same direction, and adjustable stationary contacts coöperating with the adjustable contacts of said pivoted contact member to control the activity of said electromagnets, dependent upon the position of the lever.
- 40 14. A clipper comprising a fixed cutter plate, a movable cutter plate, a lever for operating said movable cutter plate, electromagnets placed on opposite sides of said lever to oscillate it and thereby the movable cutter plate, a pivoted contact member operated from one position to the other by 45 said lever, a spring member coöperating with said pivoted contact member to yieldingly hold the contact member to either side of a central position whereby when the contact member is moved through the central position, the spring member will exert a force to complete the movement in the same direction and adjustable stationary contact members for controlling the activity of said electromagnets dependent upon the position of the lever.
- 15 16. A clipper comprising a fixed cutter plate, a movable cutter plate, a fixed handle, a pivoted handle, electrically driven means carried by the fixed handle for operating the movable cutter plate, and a switch operated by the movement of the pivoted handle with respect to the fixed handle for controlling the electrically driven means.
- In witness whereof I hereunto subscribe my signature.
- JOHN N. JOHNSON.
